UNITED STATES PATENT OFFICE.

CHARLES L. YOKOM, OF MOUNT VERNON, OREGON.

POWER-TRANSMITTING MECHANISM.

1,171,493.

Specification of Letters Patent. Patented Feb. 15, 1916.

Application filed March 22, 1915. Serial No. 16,197.

To all whom it may concern:

Be it known that I, CHARLES L. YOKOM, a citizen of the United States, residing at Mount Vernon, in the county of Grant and State of Oregon, have invented a new and useful Power-Transmitting Mechanism, of which the following is a specification.

This invention relates to power transmitting mechanism and more particularly to means for converting rotary motion into reciprocating motion whereby a long stroke of an operative member, such as a pump rod, can be produced by the rotation of a drive element.

A further object is to provide a jointed pitman of novel form having means for guiding it during its actuation by the revolute drive element, said guiding means being such as positively to prevent the pitman from leaving its proper course, during the operation of the mechanism.

Another object is to provide mechanism of this character which is simple and compact and which will not readily get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a front elevation of the power transmitting mechanism constituting the present invention, the same being shown supported by the revolute head of a windmill, the table on which said head is mounted, being shown in section and the pitman of the mechanism being illustrated at one end of its stroke. Fig. 2 is a view similar to Fig. 1 and showing the pitman at the other end of its stroke. Fig. 3 is an elevation of the opposite side of the mechanism, the pitman being shown at an intermediate point. Fig. 4 is an enlarged section on line A—B Fig. 1. Fig. 5 is a perspective view of a portion of the rack member of the pitman. Fig. 6 is an enlarged section on line C—D Fig. 3.

Referring to the figures by characters of reference 1 designates the table of a wind-

mill structure 2, this table being provided with an opening 3. Supported by the table is a revolute head 4, there being preferably a series of anti-friction balls 5 interposed between the head and table so that the said head may rotate freely. The head is adapted to carry a wind wheel, a portion of which has been shown at W and also a vane (not shown), these parts in themselves constituting no part of the present invention but being of the usual or any preferred construction.

Fixedly connected to the head 4 is a guide which extends above and below the head, this guide including an elongated frame 6 one side of which has its upper end portion inclined upwardly and inwardly as at 7 to form a deflector, said deflector merging at its upper end into a short downwardly and outwardly inclined upper end portion 8 of the other side of the frame. This last mentioned side is provided, at its lower end, with a downwardly and inwardly inclined deflecting portion 9 terminating at the upper end of a slot 10 formed in the lower portion of the frame. A groove or channel 11 is extended continuously along the inner surface of each of the sides of frame 6, along the inclined portions 7, 8 and 9, and along the walls of the slot 10. Arranged in the upper portion of the frame is a guide rail 12 parallel with but spaced from the inclined portions 7 and 8 and provided at its lower end with outwardly and laterally extending arms 13 secured to the sides of the frame 6 as shown particularly in Figs. 3 and 6. A switch 14 is pivotally connected to one side of the frame 6 near the lower portion of the incline or deflector 7 and the upper portion of this switch normally rests on the upper portion of the rail 12, it being held yieldingly in such position by a spring 15.

The head 4 is provided with an unobstructed opening between the sides of the frame 6, and secured to one side of the frame directly above the head is a cross strip 16, the lower portion of which is formed with a substantially semi-circular recess 17. An arcuate cross strip 18 is secured to the opposite side of the frame 6 and below the head 4. The back portion of frame 6 is closed at its lower end by a cross plate 19, the slot 10 thus being exposed only in the front face of the frame.

Journalized on the head 4 is a transverse shaft 20 to which the wind wheel W is con-

nected, this shaft being provided with a gear 21 located in the opening 22 formed in the head 4. A bracket 23 is secured to the lower portion of the frame 6 and is secured to the lower end of a guide rod 24, the upper end of this rod being secured to the head 4. Mounted on the guide rod is a slide 25 to which the pump rod 26 is secured. A link 27 is pivotally connected to the slide 25 and, by a bolt 26', to the lower end of a rack bar 28, the bolt 26' supporting a roller 29', the diameter of which is equal to or slightly less than the width of the slot 10. Rack bar 28 is provided with an endless series of rack teeth extending along both longitudinal edges and around both ends, the said ends of the bar being semi-circular. Some portion of the series of rack teeth is constantly in mesh with the gear 21 and the rack bar 28 is so proportioned that when the lower end of said bar is seated in the lowest portion of the slot 10, the upper portion of the bar is directly under and in mesh with the gear 21, as shown in Fig. 2. The parts are further so proportioned that when the lower end of the rack bar 28 is resting on the gear 21, the upper end of said rack is positioned in the uppermost portion of the frame 6. A guide roller 29 extends laterally from the upper portion of the rack bar 28 and is adapted to travel between the inclines 7 and 8 and the guide rod 12, this roller being located upon the uppermost portion of the guide 12 when the lower end of rack bar 28 is resting on gear 21, as shown in Fig. 1. The bar 28 and the link 27 constitute a jointed pitman.

It is to be understood that the rod 26 is preferably connected to the slide 25 by a swivel 30 and is located along the axis of rotation of the head 4. The teeth of the rack bar 28 are preferably set into the rack as shown in Fig. 5 so that the rack will operate smoothly and without mutilating its guide frame 6 and without shifting laterally out of mesh with gear 21.

It is to be understood that when the shaft 20 is rotated the gear 21 will be driven in the direction of the arrows in Figs. 1, 2 and 5 and will thrust the rack bar 28 downwardly, the roller 29 riding along the inclined deflector 9 and entering the slot 10, while the lower portion of the pitman travels within the groove 11. This downward movement results in a corresponding downward movement of slide 25 and rod 26.

When the rack bar 28 reaches its lowermost position, its upper end is shifted laterally by the rotating gear 21 and the bar is thus brought to position between said gear and one side of the frame 6 and is thrust upwardly, pulling, through the link 27, upon the slide 25. As the rack approaches its uppermost position, the roller 29 enters between the guide rod 12 and the deflector 7

and thrusts against the switch 14 so as to push the switch out of its path and against the action of spring 15. As soon as the roller passes the free end of the switch, said switch drops back onto the upper end portion of the rod 12 and thus holds the roller against return movement along the guide rail. While the roller is thus held by the switch, the lower end of the rack bar passes over the gear 21 and then begins to move downwardly between the gear and the other side of the frame 6, this movement causing the roller 29 to travel downwardly between the incline 8 and the guide rod 12. Thus it will be seen that a number of revolutions of the gear 21 will be necessary to effect one complete reciprocation of the slide 25. Consequently the mechanism not only serves to convert rotary motion into reciprocating motion, but also acts as a speed reducing means.

By providing the arcuate cross strip 18 and the arcuate recess 17 in the strip 16, the rack 28 is prevented from moving out of mesh with the gear 21 while its ends are passing the gear. For example, when the upper end of the rack 28 is passing under gear 21, the roller 29' is riding along the concentric upper edge of the strip 18, whereas while the lower end of rack 28 is passing over the gear 21, the roller 29' is passing along the wall of the recess 17.

What is claimed is:—

1. Power transmitting mechanism including a guide having upwardly converging deflectors at its upper end, a guide member spaced from and substantially parallel with said deflectors, there being a slot in the lower portion of the guide and a deflector leading thereto, a gear mounted for rotation within the guide, a rack bar having an endless series of teeth extending along opposed edges and ends thereof, said ends being rounded, an outstanding roller upon each end portion of the rack, one of said rollers being movable against and along the upper deflector and upon the guide adjacent thereto and the other roller being movable along the lower deflector and into the slot, said rack being constantly in mesh with the gear and being mounted to swing and slide within the guide, and a switch pivotally connected to the guide and adjacent one of the upper deflectors, said switch being in the path of the roller at one end of the rack.

2. Power transmitting mechanism including a guide having upwardly converging deflectors at its upper end, a guide member spaced from and substantially parallel with said deflectors, there being a slot in the lower portion of the guide and a deflector leading thereto, a gear mounted for rotation within the guide, a rack bar having an endless series of teeth extending along opposed edges and ends thereof, said ends being rounded, an outstanding roller upon each end portion of the rack, and a switch pivotally connected to the guide and adjacent one of the upper deflectors, said switch being in the path of the roller at one end of the rack.

the rack, one of said rollers being movable against and along the upper deflector and upon the guide adjacent thereto and the other roller being movable along the lower deflector and into the slot, said rack being constantly in mesh with the gear and being mounted to swing and slide within the guide, a switch pivotally connected to the guide and adjacent one of the upper deflectors, said switch being in the path of the roller at one end of the rack, a slide, a guide therefor, and a link connection between the slide and the rack.

3. Power transmitting mechanism including a guide having upwardly converging deflectors at its upper end, a guide member spaced from and substantially parallel with said deflectors, there being a slot in the lower portion of the guide and a deflector leading thereto, a gear mounted for rotation within the guide, a rack bar having an endless series of teeth extending along opposed edges and ends thereof, said ends being rounded, an

outstanding roller upon each end portion of the rack, one of said rollers being movable against and along the upper deflector and upon the guide adjacent thereto and the other roller being movable along the lower deflector and into the slot, said rack being constantly in mesh with the gear and being mounted to swing and slide within the guide, a switch pivotally connected to the guide and adjacent one of the upper deflectors, said switch being in the path of the roller at one end of the rack, and means concentric with the gear and coöperating with the respective rollers on the rack for holding the end portions of the rack in mesh with the gear while passing thereacross.

In testimony that I claim the foregoing as my own, I have hereto affixed my signature in the presence of two witnesses.

CHARLES L. YOKOM.
